BICYCLE FRAME

Donald A. Menning, 14523 Cabrillo Ave.,
Norwalk, Calif. 90650

Filed June 16, 1969, Ser. No. 17,727

Term of patent 14 years

Int. Cl. D12—11

U.S. Cl. D90—8

FIG. 1 is an elevational view of one side of a bicycle frame showing my new design;

FIG. 2 is a similar view of the opposite side;

FIG. 3 is a front elevational view thereof;

FIG. 4 is a rear elevational view; and

FIG. 5 is a top plan view.

I claim:

The ornamental design for a bicycle frame, as shown.
